(57) CLAIM

I claim the ornamental design for a yoga mat, as shown and described.

DESCRIPTION

FIG. 1 is a perspective view of a yoga mat, showing a first embodiment of my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view of FIG. 1;

FIG. 5 is a top plan view of a second embodiment thereof;

FIG. 6 is a top plan view of a third embodiment thereof;

FIG. 7 is a top plan view of a fourth embodiment thereof; and, FIG. 8 is a bottom plan view thereof.

It is understood that the front, rear, left and right-side elevational views, as well as the bottom plan view of all embodiments are identical.
